(57) **CLAIM**

The ornamental design for a baton end cap adapter, as shown and described.

DESCRIPTION

FIG. 1 is a top perspective view of a baton end cap adapter, showing my new design in a position of use with an exemplary baton;

FIG. 2 is a side elevation view thereof;

FIG. 3 is a top perspective view thereof, shown with the exemplary baton removed, to show aspects of the design not visible when combined;

FIG. 4 is a bottom perspective view thereof;

FIG. 5 is a side elevation view thereof;

FIG. 6 is a top plan view thereof;

FIG. 7 is a bottom plan view thereof; and,

FIG. 8 is a cross sectional view thereof, taken in the direction of line 8-8 on FIG. 6.

The broken lines are shown for the purpose of illustrating environmental subject matter of an exemplary baton and form no part of the claim.
